(57) **CLAIM**

The ornamental design for a sweat absorbent device as shown and described.

DESCRIPTION

FIG. 1 is a perspective view of a sweat absorbent device of my new design;

FIG. 2 is a top view of the sweat absorbent device shown in FIG. 1;

FIG. 3 is a bottom view of the sweat absorbent device shown in FIG. 1;

FIG. 4 is a left side view of the sweat absorbent device shown in FIG. 1;

FIG. 5 is a right side view of the sweat absorbent device shown in FIG. 1;

FIG. 6 is a front view of the sweat absorbent device shown in FIG. 1;

FIG. 7 is a rear view of the sweat absorbent device shown in FIG. 1; and,

FIG. 8 is an environmental perspective view of the sweat absorbent device shown in FIG. 1.

The evenly spaced broken lines within the article depict stitching that forms no part of the claimed design. The evenly spaced broken lines showing the male genitalia depict environment and forms no part of the claimed design.
